UNITED STATES PATENT OFFICE.

GEORGE W. STOLL AND GEORGE H. DRECHSEL, OF INDIANAPOLIS, INDIANA.

DEVICE FOR SECURING TABLE-LEGS.

1,301,617.

Specification of Letters Patent. Patented Apr. 22, 1919.

Application filed March 1, 1919. Serial No. 280,068.

To all whom it may concern:

Be it known that we, GEORGE W. STOLL and GEORGE H. DRECHSEL, citizens of the United States, residing at Indianapolis, in the county of Marion and State of Indiana, have invented certain new and useful Improvements in Devices for Securing Table-Legs, of which the following is a specification.

10 This invention relates to certain means for attaching legs to tables and like articles of furniture; and the object of the invention consists in providing a simple and inexpensive means whereby table legs can 15 be easily and readily attached to table tops, irrespective of slight differences in size that may be found to exist in tenons on the legs, thereby obviating the necessity of making and carrying a variety of different sizes of 20 the devices in stock.

We accomplish the above object of the invention by means of the construction illustrated in the accompanying drawings, forming a part hereof, in which—

25 Figure 1 is a perspective view of one of the devices for attaching table legs, shown in an inverted position. Fig. 2 is a top or plan view of the device as shown in Fig. 1. Fig. 3 is a front elevation of one of the devices attached to a table top, the parts being shown in an inverted position. Fig. 4 is a perspective view of a modified form of 30 one of the devices which is adapted to secure a tenon that is round in cross section.

35 Referring to the drawings, the device for attaching legs to table tops comprises in part a metal plate which is bent transversely at 9 to form a back-member 10 and a side-member 12; thence being bent at 13 to form 40 a front-member 14, and then bent at 15 to provide a wing 16. When the device is in operative position back-member 10 rests against the inner face of a depending flange 18 which is attached to the underside of 45 table top 19. Back-member 10 is secured to flange 18 by means of a screw 20 passing through an aperture 21 in an integral tongue 23 cut and bent from side-member 12, said tongue being bent to coincide with 50 the inner surface of flange 18. The free end of back-member 10 is secured to flange 18 by means of screws 27 passing through one of a series of apertures 28 in back-member 10, and the additional object of these apertures will be hereinafter described.

55 The side of the device opposite side-mem-

ber 12 is formed independently and comprises a metal plate 30 which is bent near one end to provide the transverse foot 31 to rest against the adjacent face of back-member 10. Side-member 30 is bent transversely at 33 to form a front-member 34, and is again bent at 35 to provide a wing 36 standing parallel with wing 16. These wings 16 and 36 are provided with aligned apertures 38 through which clamping-bolts 39 pass and by which side-members 16 and 36 are clamped tightly against the opposite sides of the tenon of the table leg. Any variation that may be found to exist in the width 70 of the tenons on the legs is overcome by moving side-member 30 in the proper direction along the surface of back-member 10 and securing said side-member 30 by passing the screws 27 through foot 31 and the 75 proper aperture 28 of the series in said back-member 10. After the tenon of a table leg is properly secured in the device the latter may then be fixed to the underside of 80 table top 19 by means of the screws 40 which pass through apertures 41 and 42 in the ears 43 and 44 bent out from side-members 16 and 36, while the front end of the device is secured to the table top by means of 85 the screws 47 passing through apertures 48 in ears 49 which are formed out of a part of the wings 16 and 36.

Fig. 4 shows one of the devices having a circular formation for securing a leg having a tenon which is round in cross section. 90 In the latter construction the device is blanked out as a unitary structure in which the free ends terminate in a pair of wings 55 and 56, and these in turn terminate in the laterally disposed ears 57 carrying apertures 58 through which suitable screws pass into the underside of the table top. On opposite sides and near the rear a pair of oppositely disposed ears 60 is cut and bent out of the body of the device as shown, and the 95 ears 60 are provided with apertures 61 through which screws are passed for securing the device to flange 18 of the table top 19.

The present device is so simple that further description is deemed unnecessary.

Having thus fully described our said invention, what we desire to secure by Letters Patent, is—

110 1. A table leg attaching device comprising a plate bent to provide a back, side, front member and a clamping-wing, inte-

grally formed ears on said plate for securing the latter to the table top, an adjustable side-member susceptible of adjustment along the face of the back for varying the 5 distance between the side members of the device, and means for impinging the side members of the device against the tenon of the table leg.

2. A table leg attaching device comprising a plate forming the back, one side, a 10 front member and a clamping-wing, ears formed by cutting and bending the metal from the plate for securing the latter to the

table, an independently formed side-member forming a part of the leg securing device, 15 means for adjustably securing the independent side-member to the back member of the device, and means for adjustably connecting the free ends of the side members together.

20

In witness whereof, we have hereunto set our hands and seals at Indianapolis, Indiana, this 21st day of February, A. D. one thousand nine hundred and nineteen.

GEORGE W. STOLL. [L.S.]
GEORGE H. DRECHSEL. [L.S.]
